UNITED STATES PATENT OFFICE.

ERNEST H. CARLSON, OF CHICAGO, ILLINOIS.

PROTECTING DEVICE FOR CASHIERS' CAGES.

Application filed July 5, 1921. Serial No. 482,631.

To all whom it may concern:

Be it known that I, ERNEST H. CARLSON, a citizen of the United States of America, and a resident of Chicago, county of Cook and 5 State of Illinois, have invented certain new and useful Improvements in Protecting Devices for Cashiers' Cages, of which the following is a specification.

This invention relates to protecting devices for cashier cages and the like, and particularly to that class of protecting devices in which a gravity actuated bullet-proof shield is movable into position behind the walls of the cage. 10

These devices which are now in use are objectionable, mainly for the reason that, if the cashier's hand is extended through the wicket during the operation of the device, it is subjected to serious injury by the heavy 15 shield which drops into position to close the wicket.

The main objects of the present invention are to provide an improved form of gravity operated bullet-proof shield which is instantaneously movable into position for closing all sides of a cashier's cage or the like; to provide improved means for normally suspending the shield in an invisible position within the cage; to provide electrically 25 operated means for releasing the shield; and to provide an improved form of safety device arranged to prevent injury to a hand or other object extending through the wicket at the time the protecting shield drops into 30 its closed position.

Illustrative embodiments of this invention are shown in the accompanying drawings, wherein—

Figure 1 is a front elevation of a cashier's 40 booth embodying this invention, part of the booth being broken away.

Figure 2 is a horizontal section taken on the line 2—2 of Figure 1.

Figure 3 is a rear elevation of the front 45 plate of the protecting shield as viewed from the interior of the booth.

Figure 4 is an enlarged fragmentary view of part of the shield shown in Figure 3.

Figure 5 is a transverse vertical section 50 of the shutter.

Figure 6 is a fragmentary vertical section, taken on the line 6—6 of Figure 1.

Figure 7 is an enlarged fragmentary front elevation of a booth showing a modified form of safety device. 55

Figure 8 is a vertical section, taken on the line 8—8 of Figure 7.

Figure 9 is an enlarged fragmentary horizontal section showing one of the corners of the booth and slide. 60

Figure 10 is an enlarged fragmentary vertical section of one side of the booth, showing the switch member which controls the circuit leading to the bell alarm.

Figure 11 is an enlarged fragmentary elevation of one of the electrically operated locks. 65

Figure 12 is a transverse vertical section taken on the line 12—12 of Figure 11.

Figure 13 is an enlarged elevation of one 70 of the spring sash balances.

Figure 14 is a vertical section taken on the line 14—14 of Figure 13.

The present invention may be applied to all forms of cashier cages and booths and 75 also to mail trucks and similar vehicles which are used for transporting registered mail, money and other valuables.

Referring to the drawings, the invention is applied to a cashier's booth 1, having slidably arranged therein a gravity actuated protecting shield or slide 2, which is normally retained in a suspended position in the upper part of the booth where it is invisible from the outside. 80

The booth shown in the drawings is of a form which is in general use in groceries, drug stores and mercantile houses, and comprises a frame 3, to which is secured side walls 4, a rear wall 5 having a door 6, and 90 a front wall 7 having the usual centrally located wicket 8. The usual counter or table member 9 extends around the front and side walls of the booth below the wicket.

Located in the corners of the frame 3, are 95 vertically disposed angle irons 10, which extend from the counter to the top of the frame to form guides for the vertically movable protecting shield. Carried at the lower end of each of the guides 10 is a resilient pad 11, 100 which serves as a shock absorber for the released shield.

In the form shown, the protecting slide is of box-like construction having vertically

disposed angle irons 12 secured to the four corners thereof and fitting within the guides 10 to permit a free sliding movement of the shield. In some instances, wherein it is desired to protect only the front wall of the cage, the shield 2 may consist of a single plate slidably mounted in suitable guides arranged at opposite sides of the wicket. The walls of the shield are formed of steel or other suitable bullet-proof material and are each provided with a pair of sight openings 13 through which the cashier may point a gun.

Secured to the upper edge of the slide, 15 is a pair of oppositely disposed lugs or catches 14 which engage electrically operated locks 15, mounted on the upper end of the frame 3, for normally retaining the protecting slide in a suspended position in the upper 20 part of the booth. To facilitate the lifting of the metal slide to its normal position for setting the device, the upper edge thereof is fastened to spring sash balances 16, which are mounted on the upper end of the frame 25 3. The spring balances are formed to counter balance only part of the weight of the protecting slide, so as not to retard its downward movement when the locks are released.

In order to permit the slide to drop to its 30 effective position without injury to the cashier's hand which may be resting upon the counter and extending through the wicket, either the movable shield or the stationary counter is formed with a yielding part which 35 is movable vertically relative to the member of which it forms a part. In the preferred form of construction, this yielding part is mounted on the protecting slide, and in the modified form shown in Fig. 8 it is formed 40 as part of the counter.

In the preferred form of construction, the lower edge of the front plate of the slide is provided with a centrally located recess 17, which is disposed adjacent the wicket when 45 the slide rests upon the counter 9 and pads 11. Mounted on opposite sides of the recess 17 is a pair of vertically disposed guides 18, in which is mounted vertically movable yielding part or shutter 19. Formed at the 50 ends of the lower edge of the shutter, are recesses 20, which engage pins 21, extending through the lower ends of the guides 18 for limiting the downward movement of the shutter relatively of the protecting slide. 55 The shutter is normally urged downwardly relative to the protecting shield by a pair of springs 22 carried by the shutter and secured at their lower ends to the pins 21. Extending along the lower edge of the shutter, 60 is a buffer 23 in the form of a strip of rubber, felt or other suitable material, which is doubled upon itself and secured along its edges to the inner face of the shutter by a clamping strip 24 and bolts 25.

65 In the modified form of construction

shown in Figure 8 the table member adjacent the wicket is of box-like construction, having front and rear walls 26 and 27 respectively, and a bottom member 28. The counter has a yielding part 29, which is hinged along 70 its outer or front edge to the wall 26, by hinges 30, which are arranged to permit the inner edge of the part 29 to swing downwardly into the boxlike construction. The yielding part 29 is normally held in the plane 75 of the counter by one or more compression springs 31, which bear between the yielding part and the bottom member 28. The inner faces of the members 27 and 28 are lined with plates 32 of steel or other bullet-proof 80 material. With this modified construction, if the cashier's hand is extended through the wicket at the time the slide member drops into position to close the wicket, the yielding part 29 permits the hand to be forced without injury below the plane of the counter.

Arranged along the lower edges of the walls of the booth and spaced slightly above the floor, are switch operating bars 33 for closing the electric circuit which leads to the 90 locks 15. The bars 33 carry contact members 34, which coact with other contacts 35 secured to the floor of the booth and connected with the locks 15 by the electric circuit (not shown). The bar 33 is normally urged upwardly away from the contacts 35 by compression springs 36.

Mounted on one of the side walls of the booth and extending into the path of movement of the protecting slide, is a switch 100 member or push button, 37, which is arranged to control an electric circuit (not shown) leading to a bell alarm 38, mounted on top of the booth.

In operation, the slide 2 is normally suspended in the upper part of the booth by the locks 15 and lugs 14. In cases of emergency the cashier or other person within the booth presses downwardly with one foot upon one of the bars 33 which closes the circuit leading to the locks, thereby releasing the slide. In the event that the cashier's hand is extending through the wicket and there is no opportunity to withdraw it before releasing the slide, the shutter 19, upon 110 striking the hand, will yield against the action of the springs 22 to permit the slide to drop to the limit of its movement.

Although but two specific embodiments of this invention have been herein shown and described, it will be understood that numerous details of the construction shown may be altered or omitted without departing from the spirit of this invention as defined by the following claims.

125
I claim:

1. A device of the class described comprising a booth having a wicket, a horizontal table member below said wicket, a vertically shiftable slide member arranged on said 130

- booth and shiftable into position to close said wicket, a part yieldingly arranged on one of said members and movable relative to said one member to avoid injury to an object extending through said wicket at the time said slide member shifts into position to close said wicket, and a buffer mounted on the lower edge of said yieldingly arranged part.
- 10 2. A device of the class described comprising a booth having a wicket, a horizontal table member below said wicket, a vertically shiftable slide member arranged on said booth and shiftable into position to close said wicket, a part yieldingly arranged on said slide member and movable vertically relative to said slide to avoid injury to an object extending through said wicket at the time said slide member shifts into position to close said wicket, and a buffer mounted on the lower edge of said yieldingly arranged part.
- 15 3. A device of the class described comprising a booth having a wicket, a horizontal table member below said wicket, a vertically shiftable slide member arranged on said booth and shiftable into position to close said wicket, one of said members having a recess formed therein, and a yielding part arranged on said one member in position to normally close said recess and movable relative to said one member to avoid injury to an object extending through said wicket between said recess and the other of said members at the time said slide shifts into position to close said wicket.
- 20 4. A device of the class described comprising a booth having a wicket, a horizontal table member below said wicket, a vertically shiftable slide member arranged on said booth and shiftable into position to close said wicket, one of said members having a recess formed therein, a yielding part arranged on said one member adjacent said recess and movable relative to said one member to avoid injury to an object extending through said wicket between said recess and the other of said members at the time said slide shifts into position to close said wicket, and resilient means connecting said yielding part with said one member and arranged to normally urge said part toward the other of said members into position to normally close said recess.
- 25 5. A device of the class described comprising a booth having a wicket, a horizontal table member below said wicket, a vertically shiftable slide member arranged on said booth and shiftable into position to close said wicket, one of said members having a recess formed therein in opposed relation to said wicket and the other of said members, a yielding part arranged on said one member adjacent said recess and movable relative to said one member to avoid injury to an object extending through said wicket between said
- recess and the other of said members at the time said slide shifts into position to close said wicket, a spring normally urging said yielding part toward said other member into position to close said recess, and a buffer mounted on the lower edge of said yielding part.
- 30 6. A device of the class described comprising a booth having a wicket, a horizontal table member below said wicket, a vertically shiftable slide member arranged on said booth and shiftable into position to close said wicket, said slide member having a recess formed in the lower edge thereof, and a shutter yieldingly arranged on said slide in position to close said recess, said shutter being movable vertically relative to said slide member to avoid injury to an object disposed between said table member and recess in the path of movement of said shutter.
- 35 7. A device of the class described comprising a booth having a wicket, a horizontal table member below said wicket, a vertically shiftable slide member arranged on said booth and shiftable into position to close said wicket, said slide member having a recess formed in the lower edge thereof, a shutter yieldingly arranged on said slide adjacent said recess, said shutter being movable vertically relative to said slide member to avoid injury to an object disposed between said table member and recess in the path of movement of said shutter, and a spring connecting said shutter with said slide and arranged to normally urge said shutter toward said table member into position to close said recess.
- 40 8. A device of the class described comprising a booth having a wicket, a horizontal table member below said wicket, a vertically shiftable slide member arranged on said booth and shiftable into position to close said wicket, said slide member having a recess formed in the lower edge thereof, a shutter yieldingly arranged on said slide adjacent said recess, said shutter being movable vertically relative to said slide member to avoid injury to an object disposed on said table member in the path of movement of said shutter, and a buffer mounted on the lower edge of said shutter.
- 45 9. A device of the class described comprising a booth having a wicket, a horizontal table member below said wicket, a vertically shiftable slide member arranged on said booth and shiftable into position to close said wicket, said slide member having a recess formed in the lower edge thereof, vertically disposed guides formed on said slide on opposite sides of said recess, a shutter mounted in said guides so as to be movable vertically relative to said slide member to avoid injury to an object disposed on said table member in the path of movement of said

shutter, a spring normally urging said shutter downwardly, and a buffer extending along the lower edge of said shutter.

10. A device of the class described comprising a booth having a wicket, a horizontal table member below said wicket, a vertically shiftable slide member arranged on said booth and shiftable into position to close said wicket, said slide member having a recess formed in the lower edge thereof, vertically disposed guides formed on said slide on opposite sides of said recess, a shutter mounted in said guides so as to be movable vertically relative to said slide member to 15 avoid injury to an object disposed on said table member in the path of movement of said shutter, a spring normally urging said shutter downwardly, a buffer extending along the lower edge of said shutter, and 20 means for limiting the downward movement of said shutter relatively of said slide.

11. A device of the class described comprising a wall having an opening, a stationary member adjacent said opening, a slide 25 member movable into position to close said opening, one of said members having a recess formed in opposed relation to the other of said members, and a part yieldingly arranged on said slide member and movable 30 relative to said slide to avoid injury to an object disposed between said recess and other member at the time said slide shifts into position to close said opening, said yieldingly arranged part being normally urged into 35 position to close said recess.

12. A device of the class described comprising a wall having an opening, a stationary member adjacent said opening, a slide member movable into position to close said opening, one of said members having a recess formed in opposed relation to the other of said members, and a part yieldingly arranged on said one member and normally urged into position to close said recess, said yieldingly arranged part being movable relative to said slide to permit said slide to travel to the limit of its movement toward said stationary member when the movement of said yieldingly arranged part is arrested by an object extending through said opening. 40 45 50

13. A device of the class described comprising a booth having a wicket, a horizontal table member below said wicket, a vertically shiftable slide member arranged 55 on said booth and shiftable into position to close said wicket, said slide member having a recess formed in the lower edge thereof, a shutter yieldingly arranged on said slide member and normally urged into position 60 to close said recess, said shutter being vertically movable relative to said slide member to permit said slide to travel to the limit of its downward movement when the movement of said shutter is arrested by an object extending through said wicket. 65

Signed at Chicago this 1st day of July
1921.

ERNEST H. CARLSON.
